Primary Examiner — Mary Ann Calabrese*Assistant Examiner* — Jennifer L Rempfer(74) *Attorney, Agent, or Firm* — Cantor Colburn LLP(57) **CLAIM**

The ornamental design for a band for portable information terminal, as shown and described.

DESCRIPTION

FIG. 1 is a perspective view of a band for portable information terminal, showing my new design;

FIG. 2 is a front view thereof;

FIG. 3 is a rear view thereof;

FIG. 4 is a side view thereof;

FIG. 5 is a another side view thereof;

FIG. 6 is a top view thereof;

FIG. 7 is a bottom view thereof;

FIG. 8 is a cross-sectional view taken along the line 8-8 of FIG. 1; and,

FIG. 9 is another perspective view thereof in an environment of use.

The broken lines of the information terminal in FIG. 9 are for environmental purposes only and form no part of the claimed design. The broken lines showing portions of the band for portable information terminal form no part of the claim.
